UNITED STATES PATENT OFFICE.

JOSEPH JAUCH, OF MERIDEN, CONNECTICUT, ASSIGNOR TO THE BRADLEY & HUBBARD MANUFACTURING COMPANY, OF SAME PLACE

LAMP-SHADE HOLDER.

SPECIFICATION forming part of Letters Patent No. 425,800, dated April 15, 1890.

Application filed January 6, 1890. Serial No. 336,078. (No model.)

To all whom it may concern:

Be it known that I, JOSEPH JAUCH, of Meriden, in the county of New Haven and State of Connecticut, have invented new Improvements in Lamp-Shade Holders; and I do hereby declare the following, when taken in connection with the accompanying drawings and the letters of reference marked thereon, to be a full, clear, and exact description of the same, and which said drawings constitute part of this specification, and represent, in—

Figure 1, a side view of the shade-holder as attached to a lamp; Fig. 2, a vertical central section through the ring K, showing its connection with the burner and the detachable connection of the arms L therewith; Fig. 3, a top view of the ring K; Fig. 4, a top view, and Fig. 5 a transverse section of the modification in the attachment of the arms 20 to the ring K.

This invention relates to holders for that class of shades now generally employed for the better class of central-draft lamps. The shade proper is usually made from silk crimped so as to produce a frustum-of-cone shape, and is of a very large diameter compared to the size of the lamp. These shades are made separate from the holder, the holder itself being a frame-work adapted to 25 be secured to the lamp, so that the crimped shade may be set over and supported upon the frame. The burner of these lamps is made removable from the fount, and the frames which support the shade usually consist of a ring of a diameter corresponding to 30 the lower end of the burner or collar of the fount, so as to be set thereon before the burner is in place, the burner being of larger diameter above the point where the ring is attached. The frame for the holder is made 35 from wire with arms projecting from this ring to a base-ring slightly less in diameter than the larger diameter of the shade, and arms run obliquely upward and inward from 40 this base-ring, terminating in an annular crown upon which the upper end of the shade may rest, the lower portion of the shade being supported by the base-ring.

In the more general construction of this 45 class of lamps the burner is of so great height

as to take the flame as far from the top of the fount as may be and yet permit a proper draft of oil. The arms by which the shade-holder is supported have usually run radially inward in a horizontal plane to the ring around 55 the burner; but in the larger lamps this brings the shade too low to permit the desired distribution of the light—that is, it brings the edge of the shade below the flame, whereas it is desirable that the edge of the shade shall be so far above the flame that the rays from the flame may be thrown laterally outward beneath the shade. Again, in lighting the lamp, as the burner cannot be removed in so doing, it follows that the shade 60 must remain in its place, and the lighting must be produced by reaching up under the shade. This operation exposes the shade to the danger of igniting.

Heretofore to raise the shade-holder to a 70 point above the top of the burner, as well as to permit its easy removal for lighting and trimming, a frame-work has been set around the burner, consisting of two rings, one adapted to rest on the collar or at the base of 75 the burner, where the shade is usually supported, the other at a distance above, the two being connected, so that the upper ring will form the seat upon which the shade may rest.

While this construction accomplishes the 80 objects both of elevating the shade and of permitting its easy removal, the shade-supporting frame-work must be made separate from the shade-holder and stand around the burner, and is held in place by the burner 85 itself, so that to remove the frame it is necessary to remove the burner. This frame is inconvenient, not only as being a separate structure from that of the shade-holder, but that it interferes with the trimming of the 90 lamp.

The object of my invention is to construct the shade-holder so that the shade may stand in an elevated position, be supported from the lower portion of the burner, and yet made 95 easily removable; and the invention consists in the construction, as hereinafter described, and particularly recited in the claims.

A represents the burner; B, the fount of one of the larger styles of central-draft lamps. 100

C represents the base-ring of the shade-holder, which is a ring of wire corresponding in diameter to the internal diameter of the shade near its lower edge and as usual in this class of shade-holders.

5 D represents the crown, which is made from sheet metal. It is arranged parallel to the base-ring C and connected thereto by several arms E, which are hinged at their lower end 10 to the ring C, as at F, Fig. 1, and adapted to detachably interlock with the crown, as at G, and so that the arms may be readily detached therefrom, that the arms may be folded into the plane with the ring as a convenience in 15 transportation. So far the shade-holder is of well-known construction.

To form a seat for the shade-holder which shall be of a larger diameter than the larger diameter of the burner, an auxiliary ring H 20 is set around the neck of the fount, so as to be held in place by the burner, which projects over the ring substantially as with the ring which has usually been made as a part of the shade-holder. This seat-ring is constructed with an annular seat I of a diameter 25 larger than the larger diameter of the burner above and upon which seat the shade-holder ring K may set, as clearly seen in Fig. 2.

30 To the ring C arms L are attached, preferably three or more, and they are preferably hinged to the ring C, as at M, and extend obliquely downward, their lower ends secured to the ring K. The arms L are of a length to give them a sufficient obliquity to raise the 35 shade to the desired elevation above the burner, so that the holder, while supported directly from the burner, carries the shade at the desired position above the burner.

40 From the fact of the enlargement of the ring K and the providing of the seat-ring H on the burner, the shade-holder, together with the ring K, may be raised from its seat and lifted over the burner or reset without removing the burner from its place on the fount, as 45 for lighting or trimming.

The arms L should be detachably connected to the ring K. This is best done by turning the lower ends N of the arms L upward vertically through corresponding holes in the ring K,

as seen in Fig. 2, and applying to the ends 50 projecting through the frame nuts O, and so that when the nuts are applied the ring K and the arms L are firmly united; but by removing the nuts O the arms may be detached from the ring K, and then the arms swing upward and within the ring C, as represented in broken lines, Fig. 1, and so that the arms K and the arms E are then turned into a plane substantially parallel with the plane of the ring 55 C, whence the whole structure is brought into 60 a very narrow compass for convenience in packing and transportation. The ring K may be provided with a set-screw P, by which it may be secured in place, as seen in Fig. 2.

The oblique or elevating arms L may be 65 permanently attached to the ring K, as seen in Figs. 4 and 5, as by turning the end of the arms through corresponding holes in the ring and riveting the ends of the arms thereto.

I claim—

1. The herein-described shade-holder, consisting of the auxiliary ring H, supported upon the fount and below the top of the burner and constructed with an annular seat I of larger diameter than the diameter of the 75 burner above, combined with the shade-holder consisting of a base-ring and crown connected thereto, a ring K, adapted to rest upon the said seat I, and arms L, connecting the said ring K with the base-ring of the shade- 80 holder, substantially as described.

2. The herein-described shade-holder, consisting of the auxiliary ring H, supported around the burner and below its top, constructed with an annular seat I of larger diameter than the diameter of the burner above, combined with the base-ring C, crown D, arms E, hinged to said ring and extending obliquely upward, detachably connected to the said crown, the ring K, adapted to rest upon the 90 said seat I, with arms L, hinged to the said ring C and extending inward, their inner ends detachably secured to the said ring K, substantially as described.

JOSEPH JAUCH.
